DESIGN FOR A COMBINATION BOTTLE AND STOPPER

Paul H. Ganz, New York, N. Y.

Application September 11, 1935, Serial No. 58,512

Term of patent 14 years

To all whom it may concern:

Be it known that I, Paul H. Ganz, a citizen of the United States and a resident of the city, county, and State of New York, have invented a new, original, and ornamental Design for a Combination Bottle and Stopper, of which the following is a specification, reference being had to the accompanying drawing, forming part thereof.

I claim:

The ornamental design for a combination bottle and stopper, as shown and described.

PAUL H. GANZ.
